COMBINED ELECTRIC SOLDERING AND BRAZING MACHINE

Edwin C. Kolterman, Boulder, Colo., assignor to Poudre Products Co., Inc., Fort Collins, Colo., a corporation of Colorado

Filed July 3, 1961, Ser. No. 65,800

Term of patent 3½ years

(Cl. D26—1)

FIGURE 1 is a top plan view of a combined electric soldering and brazing machine showing my new design;

FIGURE 2 is an elevational view taken from the right side of FIGURE 1, the side opposite being a mirror image thereof;

FIGURE 3 is a front elevational view of the casing portion, with the cables removed for convenience of illustration;

FIGURE 4 is a front elevational view of the tong portion thereof;

FIG. 5 is a rear elevational view of the tong portion thereof.

I claim:

The ornamental design for a combined electric soldering and brazing machine as shown and described.
